UNITED STATES PATENT OFFICE.

HARRY L. CANFIELD, OF HOMER, MINNESOTA.

LINING FOR TOBACCO-PIPES.

1,114,579.

Specification of Letters Patent.

Patented Oct. 20, 1914.

Application filed September 25, 1913. Serial No. 791,810.

To all whom it may concern:

Be it known that I, HARRY L. CANFIELD, a citizen of the United States, residing at Homer, in the county of Winona and State 5 of Minnesota, have invented new and useful Improvements in Linings for Tobacco-Pipes, of which the following is a specification.

This invention relates to improvements in linings for tobacco pipes and it proposes as 10 a new article of manufacture and sale a lining shaped to fit the stummel of the pipe and having for its purpose to artificially and favorably affect the flavor or taste of the smoke.

15 It is well known to smokers that all pipes regardless of their character are unsatisfactory when new or first used in that the flavor of the smoke is detrimentally affected by the material of the stummel and 20 the smoke is very hot as it enters the mouth, causing an unpleasant dryness and burning or "biting" of the tongue and the roof of the mouth. Ultimately, when the pipe has been "broken in", this objection is over- 25 come or substantially minimized by reason of the fact that a "crust" or deposit of tobacco tar gradually forms upon and adheres to the inner surface of the stummel and prevents the flavor of the smoke from 30 being affected by the material of the stummel and also rapidly absorbs heat from the smoke, and, hence, cools the same. In time this crust becomes so thick that it allows of only a very small quantity of tobacco 35 as a charge for the pipe. Thereupon, the crust must be removed and this is accomplished by cutting it from the stummel, an operation which is usually carelessly performed and is quite liable to injure the pipe. 40 If the crust is wholly removed or cut to an extreme thinness, the unsatisfactory smoking conditions obtaining when the pipe was new are in large measure present again and do not disappear until a new crust has suffi- 45 ciently formed. In other words, when the crust is removed, the pipe must be again "broken in" just as in the case of a new pipe. Another objection to the use of a new pipe, e. g., a pipe without any internal 50 crust or deposit, is that its stummel becomes highly heated in a very short time and if the pipe is smoked too fast the stummel, if of briar, may become burned, and if of meerschaum, may become baked and cracked, 55 especially if, when hot, it is laid on a cool surface or in a draft. The crust or deposit

which ultimately forms is a substantial protection to the stummel in that it prevents any appreciable heating thereof.

The object of the present invention is to 60 provide a lining which may be readily fitted in the stummel of a pipe and which not only prevents the flavor of the smoke from being affected by the material of the stummel, but, in fact, improves such flavor, which readily 65 adheres to the stummel as soon as the pipe is first used; which protects the stummel against heating; and which may be readily removed whenever the occasion may require without danger of injury to the pipe and as 70 readily fitted in old pipes as in new ones. In other words, the lining proposed by the present invention secures all the advantages of the crust or cake which ultimately forms in a pipe, being, in fact, an artificial substitute 75 therefor but avoids the disadvantages of such crust or cake since it makes the use of the pipe satisfactory from the outset and may be removed without endangering the stummel.

With the objects above stated in view, the invention comprises a tubular lining of compressed cured tobacco having incorporated therein a palatable artificial flavoring agent such as licorice and preferably, 85 though not necessarily, having its outer surface coated with a thin film of an adhesive substance which promotes its adherence to the pipe. This substance may advantageously be the same as the flavoring agent, 90 e. g., licorice.

The improved linings will constitute unitary articles of manufacture and sale and will be made to fit pipe stummels of various diameters. In using the lining, its outer 95 surface, preferably coated with licorice, is first moistened, and the lining is then fitted in the stummel, adhering to the surface thereof and with its upper end flush with the edge of the stummel and its lower end 100 above the bore in the stem. The lining quickly chars, after smoking, but being strongly compressed is not readily combustible and, therefore, has a long efficient life. The charring of the lining resembles the 105 natural char in an ordinary pipe and the heat developed by smoking causes the licorice to act as a cement in firmly binding the lining to the stummel. The licorice which is incorporated in the lining while inci- 110 dentally favoring the quality and aroma of the smoke is primarily a binder and pre-

vents any disintegration of the compressed tobacco. While licorice is preferred, other binders may be used, the only requirement being the selection of a binder which is palatable and will not unfavorably affect the aroma of the smoke.

The lining may be very readily adjusted to fit a particular pipe since it has a measure of flexibility and can be trimmed with a pen knife. When the pipe has been once smoked so that the lining is charred, the lining resembles the ordinary crust and, hence, its presence, as an artificial adjunct, is not noticeable. The lower end of the lining is in a plane above the bore of the stem and an enlarged cavity is thus provided at the lower end of the stummel, just as in the case of the ordinary crust, in which the smoke is cooled in its passage through the pipe. When the occasion requires, the lining can be readily removed from the stummel by using a knife, without, however, endangering the pipe, since the lining does not have the flint-like hardness of the ordinary crust nor as strong an adhesion to the surface of the stummel.

When an old lining is removed a new one may be conveniently substituted and substitutions of linings may be made throughout the life of the pipe. The linings may be used in connection with pipes of various character and in connection with false composition or meerschaum bowls which are used in the so-called sanitary pipes and as protectors for meerschaum pipes.

The invention is illustrated in the accompanying drawing in which:

Figure 1 is a vertical sectional view showing the lining fitted in the stummel of a pipe. Fig. 2 is a horizontal sectional view on the line 2—2 of Fig. 1.

Similar characters of reference designate corresponding parts in both of the views.

The lining consists of a cylindrical tubular body 1 of strongly compressed cured tobacco impregnated with a palatable binding agent, preferably licorice, and also preferably externally coated as at 2 with a palatable cementing agent, also licorice, the coating being in the form of a thin film which covers the cylindrical outer surface of the lining and also and preferably its upper end. The lining is fitted snugly in the stummel A and adheres thereto, its upper end being flush with the upper edge of the stummel and its lower end being in a plane above the bore of the stem, thus providing an enlarged cavity 3 at the lower end of the stummel in which the smoke cools during its passage through the pipe.

By the use of the lining, the unpleasant effects of smoking incident to the use of a

new pipe are avoided, the lining at the outset of the use of the pipe securing the advantages of the ordinary crust which requires considerable time for its sufficient formation.

Having fully described my invention, I claim:

1. As a new article of manufacture and sale a lining for the stummels of tobacco pipes consisting of a tubular body of strongly compressed cured tobacco.

2. As a new article of manufacture and sale a lining for the stummels of tobacco pipes consisting of a tubular body of strongly compressed cured tobacco impregnated with a palatable binding agent.

3. As a new article of manufacture and sale a lining for the stummels of tobacco pipes consisting of a tubular body of strongly compressed cured tobacco impregnated with licorice.

4. As a new article of manufacture and sale a lining for the stummels of tobacco pipes consisting of a tubular body of strongly compressed cured tobacco externally coated with a palatable cementing agent.

5. As a new article of manufacture and sale a lining for the stummels of tobacco pipes consisting of a tubular body of strongly compressed cured tobacco externally coated with licorice.

6. As a new article of manufacture and sale a lining for the stummels of tobacco pipes consisting of a tubular body of strongly compressed cured tobacco impregnated with a palatable binding agent and externally coated with a palatable cementing agent.

7. As a new article of manufacture and sale a lining for the stummels of tobacco pipes consisting of a tubular body of strongly compressed cured tobacco impregnated and externally coated with licorice.

8. As a new article of manufacture and sale a lining for the stummels of tobacco pipes consisting of a tubular body of strongly compressed cured tobacco impregnated with a palatable binding agent and externally coated with licorice.

9. As a new article of manufacture and sale a lining for the stummels of tobacco pipes consisting of a tubular body of strongly compressed cured tobacco impregnated with licorice and externally coated with a palatable cementing agent.

In testimony whereof I have hereunto set my hand in presence of two subscribing witnesses.

HARRY L. CANFIELD.
